DESIGN FOR A CHENILLE HEADDRESS

Manuel G. Rosenthal and Herbert B. Levy,
New York, N. Y.

Application January 11, 1940, Serial No. 89,395

Term of patent 3½ years

To all whom it may concern:

Be it known that Manuel G. Rosenthal, a citizen of the United States, residing at New York, in the county and State of New York, and Herbert B. Levy, a citizen of the United States, residing at New York, in the county and State of New York, have invented a new, original, and ornamental Design for a Chenille Headdress, of which the following is a specification, reference being had to the accompanying drawing, forming a part thereof.

Fig. 1 is an elevational view of the front of a chenille headdress showing my new design.

Fig. 2 is a side view thereof.

Fig. 3 is an enlarged fragmentary view showing the mesh border and solid body portion in detail.

We claim:

The ornamental design for a chenille headdress, as shown and described.

MANUEL G. ROSENTHAL,
HERBERT B. LEVY.
